US0D1036536S

(12) **United States Design Patent** (10) **Patent No.:** **US D1,036,536 S**
(45) **Date of Patent:** **** Jul. 23, 2024**

(54) **CAMERA**

- (71) Applicant: **GoPro, Inc.**, San Mateo, CA (US)
(72) Inventors: **Huy Phuong Nguyen**, Alpine, UT (US); **Senka Agic Bergman**, Montara, CA (US); **Daniel J. Coster**, Oakura (NZ)
(73) Assignee: **GoPro, Inc.**, San Mateo, CA (US)
(**) Term: **15 Years**
(21) Appl. No.: **29/894,709**
(22) Filed: **Jun. 13, 2023**

Related U.S. Application Data

- (60) Continuation of application No. 29/726,066, filed on Feb. 28, 2020, now Pat. No. Des. 998,017, which is a continuation of application No. 29/699,945, filed on Jul. 30, 2019, now Pat. No. Des. 890,835, which is a division of application No. 29/631,230, filed on Dec. 28, 2017, now abandoned.

- (51) **LOC (14) Cl.** **16-01**
(52) **U.S. Cl.** **D16/202**

(57)

CLAIM

The ornamental design for a camera, as shown and described.

DESCRIPTION

FIG. 1 is a top, front and right side perspective view of a camera showing our new design;

FIG. 2 is a top, rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings depict portions of the camera that form no part of the claimed design.

1 Claim, 7 Drawing Sheets
